VENDING MACHINE

Maurice J. Auerbach, Cleveland Heights, Ohio, assignor to Standard Vendors, Inc., Cleveland, Ohio, a corporation of Ohio

Application October 9, 1943, Serial No. 505,600

8 Claims. (Cl. 312—67)

This invention relates, as indicated, to vending machines, but has reference more particularly to vending machines which are especially adapted for the distribution of packaged merchandise, such as cigarettes, candy, etc.

A primary object of the invention is to provide a machine in which the merchandising capacity is increased by a novel arrangement of the article ejecting mechanism.

Another object of the invention is to provide a machine in which packages of different sizes may be merchandised.

A further object of the invention is to provide a novel form of ejecting mechanism.

A still further object of the invention is to provide a novel compact arrangement of package receptacles.

Other objects and advantages of the invention will be apparent during the course of the following description.

In the accompanying drawings, forming a part of this specification, and in which like numerals are employed to designate like parts throughout the same:

Fig. 1 is a fragmentary perspective view of a vending machine, such as may have incorporated therein mechanism made in accordance with the invention.

Fig. 2 is a cross-sectional view, taken on the line 2—2 of Fig. 3, showing the package ejecting mechanism of the present invention;

Fig. 3 is a fragmentary cross-sectional view, taken on the line 3—3 of Fig. 2, and

Fig. 4 is a fragmentary cross-sectional view, taken on the line 4—4 of Fig. 2.

Referring more particularly to the drawings, it will be seen that a cigarette vending machine, such as is particularly adapted to have the ejecting mechanism or means of the present invention incorporated therein comprises a frame 1 disposed forwardly of the machine and a frame 2 disposed rearwardly of the machine and at a somewhat higher elevation than the frame 1.

The frame 1 is adapted to support a horizontal row of magazines or receptacles 3 arranged to provide spaces 4 therebetween; each receptacle adapted to contain a stack of the articles to be dispensed, shown in this instance as packages 5 of king-size cigarettes. Similarly, the frame 2 is adapted to support a horizontal row of magazines or receptacles 6 arranged substantially in abutment with each other, and each adapted to contain a stack of the articles to be dispensed, shown

in this instance as packages 7 of ordinary or regular size cigarettes.

Each of the receptacles 3 is provided at the rear thereof and adjacent its lower end with a door or closure 8, which is normally disposed vertically, but which is pivotally mounted as at 9 to permit swinging of the same rearwardly when one of the packages 5 is ejected through the opening 10 at the lower rear portion of the receptacle. Similarly, each of the receptacles 6 is provided at the rear thereof and adjacent its lower end with a door or closure 11, which is normally disposed vertically, but which is pivotally mounted as at 12 to permit swinging of the same rearwardly when one of the packages 7 is ejected through the opening 13 at the lower rear portion of the receptacle.

The frames 1 and 2 are stationarily mounted on the vending machine, the frame 1 being shaped to provide a cavity or recess 14, in which is mounted a multiplicity of pull handles 15 and 16, the handles 16 being arranged alternately with the handles 15, and being designed for use in ejecting packages from the receptacles 6, whereas the handles 15 are designed for use in ejecting packages from the receptacles 3.

Each of the handles 15 and 16 is mounted for reciprocal movement relative to the recess 14, and each is provided with a longitudinally extending slot 17, through which a stop rod or bar 11a extends, this bar being designed to prevent the handles 15 and 16 from being pulled beyond their outermost position.

Pivots connected to each of the pull handles 15 adjacent its rear end is a lever 18 having an ejector head 19, the lower end of the lever being pivoted as at 20 to a bearing 21, which, in turn, is rigidly secured to the apron or skirt 22 which forms a part of the frame 1. The pivot pin 23, which connects the lever 18 to the handle 15 is movable in a vertical slot 24 in the handle, which slot is provided to accommodate the change in the point of pivotal connection between the handle and lever occasioned when the handle 15 is pulled forwardly.

When it is desired to eject a package from one of the receptacles 3, the necessary coins are deposited in the machine, permitting the handle 15 for that receptacle to be moved to the position indicated in dotted lines in Fig. 3, and causing the lever 18 to be moved to the position likewise indicated by the dotted lines, the lever moving through slots 25 and 26 in the frame and through a slot 27 in the lower end of the receptacle. Incidental to this movement, the ejector head 19 lifts

all of the packages in the receptacle, but after such head has moved to the dotted line position in Fig. 3, the packages are dropped to a lower position in the receptacle. Upon pushing the handle 15 inwardly, the various parts are restored to their initial position, as shown by the solid lines, and the ejector head 19, incidental to its return to such initial position, forcibly ejects the lowermost package 5 through the opening 10, as indicated in Fig. 3, the package swinging the door 8 outwardly.

Rigidly secured to each of the pull handles 16 adjacent the rear end thereof is a bracket 28 which extends through slots 29 and 30 in the frame 1 and has a vertical extension 31, which extends into one of the spaces 4 between the receptacles 3. The extension 31 is pivoted, as at 32 to one end of a link or connecting bar 33, the opposite end of which has secured thereto and extending transversely thereof a pivot pin or stub shaft 34, to which a lever 35 is pivotally secured, as at 36. The lever 35 is pivotally connected to the frame 2, as at 36', but this pivotal connection is movable in a slot 37. The lever, moreover, is provided at its upper end with an ejector head 37' similar to the head 19, the head 37' extending through a slot 38 in the frame 2 and through a slot 39 in the lower end of the receptacle 6. The pivotal connection of the lever 35 to the pin 34 is made at such a point that the ejector head is movable along the median plane 3-3 (Fig. 2) of the packages in the receptacle 6.

When it is desired to eject a package from one of the receptacles 6, the necessary coins are deposited in the machine, permitting the handle 16 for that receptacle to be moved to the position indicated in dotted lines in Fig. 4, and causing the lever 35 to be moved to the position indicated by the dotted lines, the lever moving through the slots 38 and 39. Incidental to this movement, the ejector head 37' lifts all of the packages in the receptacle, but after such head has moved to the dotted line position in Fig. 4, the packages are dropped to their lower position in the receptacle. Upon pushing the handle 16 inwardly, the various parts are restored to their initial position, and the ejector head 37', incidental to its return to such initial position, forcibly ejects the lowermost package 7 through the opening 13, as indicated in Fig. 4, the package swinging the door 11 outwardly.

It will be noted that the operative elements 31 and 33 are disposed in the spaces 4 between the receptacles 3, thereby utilizing space which is usually present in machines of this type and which is usually wasted.

In any event, by providing these spaces between the receptacles 3, which spaces are relatively narrow and would not, therefore, in the aggregate, greatly increase the width of the machine, I am enabled to provide the rear row of receptacles and thereby at least double the merchandising capacity of the machine, it being noted that the packages are ejected from the rear row of receptacles entirely independently of the ejection of packages from the front row.

Moreover, since the links 33 are disposed below the upper portion of the frame 2 and need not extend into the spaces between the receptacles 6, such receptacles may, as shown in Fig. 2, be placed closer to each other than the receptacles 3, thereby permitting a greater number of receptacles to be placed in the rear row than in the front row, and to that extent, more than

doubling the merchandising capacity of the machine. In the present instance the ratio of the number of receptacles in the rear row to the number in the front row is approximately 4½ to 4, but this ratio may be varied within predetermined limits.

Although the machine has been described particularly with reference to the merchandising of cigarette packages, it is to be understood that the novel ejecting means and receptacle arrangement of the invention may be incorporated in any machine designed to vend either packaged or bulk goods.

It is to be understood that the form of my invention, herewith shown and described, is to be taken as a preferred example of the same, and that various changes in the shape, size and arrangement of parts may be restored to, without departing from the spirit of my invention, or the scope of the subjoined claims.

Having thus described my invention, I claim:

1. In a machine of the character described, a row of spaced receptacles, a second row of receptacles disposed rearwardly of the first row and means for ejecting articles from said second row of receptacles, said means including elements disposed in the spaces between the receptacles in said first-named row.

2. In a machine of the character described, a row of spaced receptacles, a second row of receptacles disposed rearwardly of the first row, and means for ejecting articles from said second row of receptacles, said means including a bracket and connecting link, at least portions of which are disposed in the spaces between the receptacles in said first-named row.

3. In a machine of the character described, a row of receptacles, a second row of receptacles disposed rearwardly of the first row, means for ejecting articles from the receptacles in the first row, said means including a series of pull handles disposed below said first-named row of receptacles, and means for ejecting articles from the receptacles in the second row, said means including a series of pull handles disposed in the spaces between said first series of handles.

4. In a machine of the character described, a row of receptacles, a second row of receptacles disposed rearwardly of the first row, means for ejecting articles from the receptacles in the first row, said means including a series of spaced pull handles disposed below said first-named row of receptacles, and means for ejecting articles from the receptacles in the second row, said means including a series of pull handles disposed at a level below said first-named row of receptacles and arranged alternately with said first-named handles.

5. In a machine of the character described, a row of receptacles, a second row of receptacles disposed rearwardly of the first-named row of receptacles, and means for ejecting articles from said second-named row of receptacles, said means including pull handles disposed at a level below said first-named row of receptacles, brackets secured to said pull handles, connecting links secured to said brackets, and ejecting levers secured to said connecting links.

6. In a machine of the character described, a row of spaced receptacles, a second row of receptacles disposed rearwardly of the first-named row of receptacles, and means for ejecting articles from said second row of receptacles, said means including pull handles disposed below said first-named row of receptacles, brackets having

extensions which extend into the spaces between said first-named row of receptacles, connecting links connected to said extensions and having portions extending into said spaces, and ejecting levers operably connected to said links.

7. In a machine of the character described, a row of receptacles disposed adjacent the front of said machine, a second row of receptacles disposed rearwardly of the first row, means for ejecting articles from said first row of receptacles, and means operable independently of said first-named means for ejecting articles from the receptacles in said second row, said second row ejecting means including handles disposed along the front of said machine in vertical planes

15 which are parallel with the receptacles in said first row and extend through the space between the receptacles in said first row.

5 8. In a machine of the character described, a row of receptacles, a second row of receptacles disposed rearwardly of the first row, means including handles disposed along the front of said machine for ejecting articles from said first row of receptacles, and means including handles disposed along the front of said machine, arranged alternately with said first-named handles and operable independently of said first-named ejecting means for ejecting articles from the receptacles in said second row.

MAURICE J. AUERBACH.
